Inventor,

Theodore Zanger.

UNITED STATES PATENT OFFICE.

THEODOR ZANGER, OF BUFFALO, NEW YORK, ASSIGNOR TO J. B. SWEET
& SON, OF SAME PLACE.

SUPPORT FOR CARRIAGE-TOPS.

SPECIFICATION forming part of Letters Patent No. 341,090, dated May 4, 1886.

Application filed June 24, 1884. Serial No. 135,935. (No model.)

To all whom it may concern:

Be it known that I, THEODOR ZANGER, a citizen of the United States, residing at the city of Buffalo, in the county of Erie and State 5 of New York, have invented a new and useful Improvement in Carriage-Tops, of which the following is a specification.

My invention relates to children's carriages, and is a device for supporting the rod of a 10 parasol or canopy-top thereon.

The object of my invention is to provide a supporting device controllable by a single screw, and one which will serve as a means to render a parasol, umbrella, or canopy-top adjustable either vertically or laterally, or both 15 vertically and laterally. I attain these objects by the mechanism illustrated in the accompanying drawings, in which—

Figure 1 is a perspective view of the several 20 parts constituting the device; and Fig. 2 is a similar view, partly in section, of the whole device when put together.

Similar letters refer to similar parts in both views.

25 A designates a centrally-perforated base-piece, having means for attaching it to the seat of a child's carriage or other support.

B is a sort of eyebolt, having a screw-thread, 30 b, and provided with thumb-nut D, and having a flat circular head with beveled inner edge, and designed to fit tightly within the central perforation in A.

C is a funnel-shaped piece, having an opening, c, on either side, and is designed to be 35 placed over B and receive and transmit to E the pressure of the nut D.

E represents a supporting-rod, such as are used upon children's carriages for supporting a parasol or a canopy-top.

40 The operation of the device is as follows: The several parts of the device having been properly adjusted together and attached to their support, the rod E is inserted through the opening c, the eye of B, and the opening 45 c upon the opposite side of C. The thumb-nut D is then forced home, thereby forcing C against E, and securely clamping it between

the outer edges of A and C, and holding it firmly in place. To adjust the rod E, loosen D, when the rod will be free to move, and 50 the parasol, umbrella, or canopy-top which it supports may be raised or lowered, or thrown either to the right or left, and when thus adjusted is firmly held in place by simply forcing the thumb-nut D.

If desired, the edges in the central perforation in d and the beveled edge of the head of B may be milled, so as to increase their friction, or they may be provided with cogs; and the device may be attached to the driver's seat 60 upon truck-wagons and other carriages, as a support for the staff of an umbrella, or it may be attached to the pommel of a saddle for the same purpose; and it is obvious that the skilled mechanic will readily construct a variety of devices which will accomplish the 65 same results without departing from the spirit of my invention.

I am aware of Patent No. 258,798, of 1882, in which the eyebolt has but a narrow bearing 70 in the base, and a bearing-block engages the umbrella-shank close the eyebolt. In my device the eyebolt has a wide circular base, b', which gives it a firm bearing in the base-plate A, and the friction-cone presses the umbrella-shank to the base at two points distant from the eyebolt. This makes a very firm joint, and allows the shank to be held close to the plate—a result which cannot be accomplished in the 75 patent cited.

80 What I claim as new is—
The combination, with the base-plate A, having a dovetailed circular aperture, and the eyebolt B, having a large circular base corresponding therewith, of the friction-cone C, having 85 recesses c, which engage the shank E at points distant from the eyebolt, and the nut D, all constructed and arranged to hold the shank flat against the plate A, as set forth.

THEODOR ZANGER.
